Geo. P. Kimmel.
ATTORNEY.

UNITED STATES PATENT OFFICE

HOWARD L. SMITH, OF LEXINGTON, KENTUCKY

TOBACCO PRESS

Application filed December 9, 1929. Serial No. 412,872.

This invention relates to a tobacco press adapted to be applied to tobacco after the same has been stripped and hung on sticks for the purpose of making the tobacco easy to handle and to retain the same in a case condition.

One of the objects of the invention is to provide, in a manner as hereinafter set forth, a press for the purpose aforesaid in which successive quantities of tobacco may be pressed within a pressure chamber without removing any of the pressed quantities therefrom and in which the pressure chamber is externally braced coincidentally with the application of pressure to the tobacco therein.

A further object of the invention is to provide a tobacco press having the foregoing characteristics, which is simple in construction, positive and efficient in operation, and inexpensive to manufacture.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the same:—

Figure 1 is a side elevation of a tobacco press in accordance with this invention.

Figure 2 is a top plan thereof.

Figure 3 is an enlarged transverse section taken on the line 3—3 of Figure 1.

Figure 4 is a longitudinal section taken on the line 4—4 of Figure 2.

Figure 5 is a reduced detail view showing the retaining board in elevation.

A press in accordance with this invention

includes a pair of rear supporting posts 1 arranged in spaced relation and connected together by means of a pair of braces 2. The braces 2 are preferably formed of metal and are arranged to intersect each other with each

brace connecting the upper end of one of the posts 1 with the other of said posts at a point spaced from the lower end of the latter. The press further includes a pair of front supporting posts 3 which are arranged in spaced relation and connected together by means of an end board 4 which extends from the upper ends of the posts to a horizontal plane spaced from the lower ends thereof. Extending between the front posts 3 and rear posts 1 is a pair of side boards 5 which are preferably dove-tailed or mortised into the supporting posts and which have their outer side faces flush with the outer side faces of the posts. The supporting posts, end board and side boards are preferably formed of wood, although they may be formed of metal if desired. Seated on the side boards 5 is a pair of top rails 6, the ends of which are preferably dove-tailed or mortised into the posts, and the outer side faces of which are flush with the outer side faces of the posts. Extending between the front and rear supporting posts, in spaced relation to the lower edges of the side boards 5, is a pair of bottom rails 7 which are preferably dove-tailed or mortised into the posts with the outer side faces of the strips 7 flush with the outer side faces of the posts.

The connections between the supporting posts and top and bottom rails are reinforced by metal plates 8 which are secured to the outer side faces of the rails and posts. Mounted on the upper faces of the top rails 6 is a pair of channeled, longitudinally extending tracks 9 formed of any suitable metal. The tracks 9 are of less width than the rails 6 and the inner side faces thereof are substantially flush with the inner side faces of the rails. The supporting posts, end board and side boards provide a pressure chamber 10 which is open at its top and bottom and also at its rearward end, with the exception of the braces 2 extending diagonally across the rearward end.

Disposed within the chamber 10, and projecting thereabove, is a press board 11, the width of which is slightly less than the space between the side boards 5. Secured to the upper edge of the press board 11 is a top cross piece 12 which extends transversely of

the press with the ends of the piece 12 projecting beyond the side boards 5. Depending from the cross piece 12 is a pair of brackets 13 to provide bearings for rollers 14 which 5 ride on the tracks 9 to support the press board 11. Secured to the lower edge of the press board 11 is a bottom cross piece 15 which extends transversely of the press with its ends 10 projecting through spaces 16 between the side boards 5 and bottom rails 7. Depending from the bottom cross piece 15 is a pair of brackets 17 to provide bearings for horizontally disposed rollers 18 which ride along the upper portions of the inner faces of the bottom rails 7 to provide guides for the press board 11.

Connecting the ends of the cross pieces 12 and 15 is a pair of vertically disposed draw bars 19 which are provided intermediate their 20 ends with lugs 20 to which are secured chains 21 which extend in a forward direction and pass over sprockets 22 fixedly mounted on a shaft 23 which extends transversely of the press and is rotatably mounted in spaced bearings 24 projecting from the forward faces of the front posts 3. The links of the chains 21 are of flat formation, each being provided with an opening 25 for the reception of the teeth 26 of the sprockets 22.

30 The shaft 23 is actuated by means of a suitable lever 27 attachable to either end of the shaft. The chains 21 are prevented from jumping off the sprockets 22 by means of guards 22' which are secured to the posts 3 and project over the sprockets 22. Fixedly mounted on the shaft 23 intermediate the ends of the latter is a ratchet wheel 28, the teeth of which are adapted to be engaged by a pawl 29 pivotally connected to a bracket 30 secured to and projecting from the forward face of the end board 4. Projecting from the rear face of the press board 11 is a pair of spaced lugs 31 to which are connected the outer ends of a pair of rearwardly and inwardly inclined chains 32. The inner ends of the chains 32 are secured to the upper end of a chain 32', the lower end of which is secured to the bottom cross piece 15, and which extends from the cross piece at an upward and rearward inclination. Connected with the chains 32 and 32' is a rope 33 which is adapted to be wound around a windlass 34 rotatably mounted in a substantially U-shaped bracket 35 which is preferably formed 50 of metal and welded or otherwise secured to one of the braces 2.

In the operation of my improved press, sticks such as 36, having tobacco, as indicated at 37, suspended therefrom, are extended 60 across the press to rest on the rails 9 with the tobacco 37 depending into the chamber 10 between the end board 4 and press board 11. The board 11 is then drawn toward the end board 4 by manipulation of the lever 27 by 65 means of which the tobacco 37 is tightly

pressed between the press board 11 and the end board 4. During the pressing operation the side boards 5 are automatically protected against outward bulge by means of a pair of elongated rollers 38 which are provided at 70 their ends with pintles 39 rotatably mounted in the cross pieces 12 and 15. The rollers 38 are disposed between the draw bars 19 and side boards 5 in close proximity to the latter and in rolling contact with the outer faces 75 thereof.

After the tobacco 37 has been pressed between the press board 11 and end board 4, the tobacco may be retained in a pressed condition within the chamber 10 if desired, by 80 means of a retaining board 40, while another supply of tobacco is pressed between the retaining board 40 and press board 11. The board 40 is preferably provided at its side edges with longitudinally extending strips 85 41 which are formed at their upper ends with outwardly projecting handles 42 which extend over the tracks 9. Formed in the upper edges of the top rails 6 are a plurality of 90 spaced openings 43 for the reception therein 90 of removable pins 44, which project upwardly from the top rails into abutment with the rear faces of the handles 42 to retain the retaining board 40 in position at the upper end of the latter. The board 40 is maintained in position at its lower end by means of resilient latching devices 46 which are secured to the inner faces of the bottom rails 7 adjacent the lower edges of the latter, and outside the paths of travel of the guide rollers 18. As many sets of the latch members 46 may be provided as desired with each latch member disposed in vertical alignment with one of the openings 43. Only one set of the latch members is used to retain the board 40 in position, such set depending upon the position longitudinally of the press in which it is desired to secure the retaining board. 100

The purpose of the windlass 34 and chains 32 and 33 is to draw the press board 11 in a rearward direction preparatory to the positioning of tobacco between the press board 11 and end board 4. When operating the windlass 34, the pawl 29 is swung upwardly about its pivot to inoperative position. 110

It is thought that the many advantages of a tobacco press in accordance with this invention will be readily apparent, and although the preferred embodiment of the invention is as illustrated and described, it is 120 to be understood that changes in the size, shape and arrangement of parts may be resorted to, so long as such changes fall within the scope of the invention as defined in the appended claims. 125

What I claim is:

1. A tobacco press comprising, means to provide a pressure chamber having a closed end and a pair of closed sides formed with longitudinally extending slots, a press board 130

extending into the chamber transversely thereof and projecting above the latter, a top cross piece secured to the upper edge of the press board and having its ends projecting beyond the sides, bearing brackets depending from the top cross piece, rollers rotatably mounted in the bearing brackets and resting on the upper edges of the sides to support the press board, a bottom cross piece secured to the lower edge of the press board and having its ends projecting through the slots in the sides, bearing brackets depending from the bottom cross piece, horizontally disposed rollers rotatably mounted in said last named bearing brackets and engaging the inner faces of the sides to provide guides for the press board, vertically disposed draw bars connecting the ends of the top and bottom cross members, means for applying force to the draw bars longitudinally of the chamber to move the press board toward the closed end of the chamber, and elongated rollers disposed between the draw bars and sides, said rollers being rotatably mounted on the top and bottom cross pieces and being disposed in close proximity to the outer faces of the sides.

2. A tobacco press comprising, means to provide a pressure chamber having a closed end and a pair of closed sides formed with longitudinally extending slots, a press board disposed within the chamber transversely thereof, supporting means for the press board rigidly connected therewith and having 35 rolling contact with the upper edges of said sides, guiding means for the press board rigidly connected therewith and having rolling contact with the inner faces of said sides, external bracing means for said sides rigidly 40 connected with the press board and having rolling contact with the outer faces of said sides, and means for forcibly moving the press board toward said closed end.

3. A tobacco press comprising, means to provide a pressure chamber, the sides of the chamber being adapted to support sticks having tobacco depending therefrom into the chamber, a press board movable within the chamber for compressing the tobacco therein, and means carried by the press board for externally bracing the sides of the chamber at 50 points adjacent the press board.

4. A tobacco press comprising, means to provide a pressure chamber having a closed end and a pair of closed sides formed with longitudinally extending slots, said sides being adapted to support sticks having tobacco depending therefrom into the chamber, a press board disposed within the chamber 55 transversely thereof, means for forcibly moving the press board toward the closed end of the chamber to press the tobacco therein, external bracing means for said sides, said bracing means being rigidly connected with 60 the press board, and a removable retaining

board adapted to be engaged with said sides to retain the tobacco in a pressed condition within the chamber.

5. A tobacco press comprising, means to provide a pressure chamber having a closed end, the sides of the chamber being adapted to support sticks having tobacco depending therefrom into the chamber, a press board disposed within the chamber transversely thereof, means for forcibly moving the press board toward the closed end of the chamber to compress the tobacco therein, vertically disposed rollers in contact with the sides to externally brace the latter, said rollers being rigidly connected with the press board, and a retaining board adapted to be engaged with the sides of the chamber to maintain the board against the compressed tobacco to retain the latter in its compressed condition.

In testimony whereof, I affix my signature hereto.

HOWARD L. SMITH.
